UNITED STATES PATENT OFFICE.

HIRAM D. CURRIER, OF CHICAGO, ILLINOIS.

TELEPHONY.

No. 907,470.

Specification of Letters Patent.

Patented Dec. 22, 1908.

Application filed July 20, 1908. Serial No. 444,396.

To all whom it may concern:

Be it known that I, HIRAM D. CURRIER, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephony and its objects and advantages will be well understood by reference to the accompanying drawing, in which—

Figure 1 shows one embodiment thereof, and Fig. 2 another embodiment thereof.

Referring first to the embodiment of the invention shown in Fig. 1, I have illustrated a metallic circuit *a* which is shown as connecting a telephone station 1 (which, for example, may be a train despatcher's office) with four or other number of telephone stations, 2, 3, 4 and 5. Each telephone station includes a bridge conductor *b* uniting the metallic sides of the telephone line *a* (though it is to be understood that I do not limit my invention to metallic telephone circuits), within which bridge conductor there is included at each station a telephone switch-hook *c*, a receiver *d* and the secondary *f* of an induction coil. Each bridge conductor *b* at the stations 2, 3, 4 and 5 also includes a retardation coil *c'* that serves to determine the effective resistance offered to the talking current impressed upon said bridge conductor at the line. The primary *g* of the induction coil at each telephone station is shown included in a local circuit with a transmitter *h* and a battery *i*, which may, if desired, be of eleven volts pressure. There is also shown at each station a shunt conductor *k*, which includes a retardation coil *l* of low ohmic resistance. The conductor *k* and the local circuit for the transmitter *h* include each a pair of contacts *m* and *n*, respectively, the contacts of each of the sets *m* and *n* being normally in separated relation. The contacts of both sets are simultaneously engaged upon the operation of a key *o*, the operation of which key is to occur when the receiver *d* of the associate station is removed from its switch-hook *c* and when the party at such station is to talk. When the party at such station is to listen, the button *o* is released. If the train despatcher or other party is talking at the station 1, the receiver thereat is

shunted by the conductor *k* upon the operation of the button *o*, the associate transmitter circuit *g h i* being at the same time closed. By the closure of the contacts *m* at station 1, a conductance path of comparatively low effective resistance is established about the telephone receiver *d*. By this feature of my invention I am enabled to eliminate a large portion of the effective resistance to the outgoing voice currents that are impressed upon the secondary *f* as a consequence of the operation of the transmitter *h*. The conductor *k* at each of the stations 2, 3, 4 and 5 not only establishes a shunt about the telephone receiver *d* at each of said stations when said conductor *k* is closed at *m* at each station, but said conductor *k* at each station is also so connected as to shunt the retardation coil *c'* thereat as well. By shunting the receiver *d* and retardation coil *c'*, when talking, the effective resistance offered to the flow of impressed voice currents from the secondary *f* to the line is not only reduced, but side tones at the receivers *d* are eliminated, which is also the case with the receiver at station 1 when the shunt conductor *k* thereat is closed at *m*. It is to be understood that the key *o* at a station is operated only when voice currents are to be impressed upon the line at such station and that such key *o* is to be released when voice currents are to be received at such station, the strength of the batteries *i* incidentally being saved by opening the transmitter circuits during the time the receivers have the shunts removed therefrom.

Much difficulty has been experienced in the past in equally distributing the voice currents to a plurality of telephone stations which were connected simultaneously to a telephone line when the despatcher desired to convey the same information to a number of stations, as is the case in putting out a train order. I overcome this difficulty by suiting the effective resistance of each bridge conductor *b* to its distance from the despatcher's office or other station, 1. Thus, where retardation coils *c'* are employed, the effective resistance of the bridge conductor at station 2 is caused to be greater by the retardation coil *c'* than the effective resistance of the bridge conductors *b* at the other train line stations that are more remote from the despatcher's office 1; the effective resistance of the bridge conductor *b* at train line station 3 is made less than the effective resistance of the bridge conductor at the train line station

2, but greater than the effective resistances of the bridge conductors at stations 4 and 5, that are more remote from the despatcher's office 1 than stations 2 and 3; the effective 5 resistance of the bridge conductor at station 4 is less than the effective resistance of the bridge conductors at stations 2 and 3 and greater than the effective resistance of the bridge conductor *b* at station 5. The effective 10 resistances offered by the bridge conductors *b* at stations 2, 3, 4 and 5 are desirably made adjustable, and such adjustment may be accomplished where retardation coils are employed by having the cores for said 15 coils slidable within the bores of said coils. By thus varying the effective resistances of the bridge conductors at the different train line stations, the effectiveness of the voice currents received at each of such stations 20 may be made approximately equal. This is due to the fact that the impedance or effective resistance of the different bridges is tapered in value from the despatcher's end of the line to the other end thereof. For example, 25 it is possible with this arrangement to so adjust the effective resistance of the conductor *b* at station 2, that it is equal to the effective resistance of the corresponding conductor of the station at the other end of the 30 line plus the line resistance.

The retardation coil *l* included in each shunt conductor *k* has an adjustable core to vary the effect of the shunt upon the circuit including the receiver. The purpose of this 35 adjustable impedance which is normally low in value, is to permit voice currents to pass through the receiver, provided the despatcher desires to interrupt the person talking at any one of the stations. It being desirable to 40 have this impedance low so as not to dissociate outgoing voice currents from the stations, it is found preferable to make it adjustable so that the "break in" feature described above may be obtained. In practice, it is 45 found only necessary that the person talking should receive enough current to know that the despatcher is on the line, in which event the party talking releases the key *o* and receives the full talking current from the line.

50 The effective resistance offered by the small retardation coil *l* at each train line station that is nearer the transmitting station, is caused to be greater than that offered by each more distant impedance coil *l*. The adjustment of the effective resistances at each 55 of the train line stations 2, 3, 4 and 5 may also be accomplished, as shown in Fig. 2, by substituting condensers *p* for the retardation coils *c* at such stations, the capacity of the 60 condensers increasing with the distance of the train line stations from the despatcher's office. In other respects the system shown in Fig. 2 is similar to the system shown in Fig. 1. In neither of these systems have I 65 deemed it necessary to illustrate the signal-

ing devices that are located at the different stations.

While I have herein shown and particularly described preferred embodiments of my invention and the adaptation thereof to train 70 line circuits, I do not wish to be limited thereto, as changes may readily be made without departing from the spirit of the invention.

Having thus described my invention, I 75 claim as new and desire to secure by Letters Patent the following:

1. A telephone system including a telephone line, a transmitting station at which voice currents are impressed upon the line, 80 a plurality of receiving stations having telephone receivers included in conductors in bridge of the telephone line, and which conductors offer differing degrees of effective resistance to the voice currents impressed 85 thereupon by the transmitting station, each bridge conductor that is nearer the transmitting station having more effective resistance than each more distant bridge conductor.

2. A telephone system including a tele- 90 phone line, a transmitting station at which voice currents are impressed upon the line, a plurality of receiving stations having telephone receivers included in conductors in bridge of the telephone line, and which conductors offer differing degrees of adjustable 95 effective resistance to the voice currents impressed thereupon by the transmitting station, each bridge conductor that is nearer the transmitting station having more effective 100 resistance than each more distant bridge conductor.

3. A telephone system including a telephone line, a transmitting station at which voice currents are impressed upon the line, a 105 plurality of receiving stations having telephone receivers included in conductors in bridge of the telephone line, and which conductors offer differing degrees of impedance 110 to the voice currents impressed thereupon by the transmitting station, each bridge conductor that is nearer the transmitting station having more impedance than each more distant bridge conductor.

4. A telephone system including a tele- 115 phone line, a transmitting station at which voice currents are impressed upon the line, a plurality of receiving stations having telephone receivers included in conductors in bridge of the telephone line, and which conductors offer differing degrees of adjustable 120 impedance to the voice currents impressed thereupon by the transmitting station, each bridge conductor that is nearer the transmitting station having more impedance than 125 each more distant bridge conductor.

5. A telephone system including a tele- 130 phone line, a transmitting station at which voice currents are impressed upon the line, a plurality of receiving stations having tele-

phone receivers included in conductors in bridge of the telephone line, the effective resistance of said conductors being adjustable.

6. A telephone system including a telephone line, a transmitting station at which voice currents are impressed upon the line, a plurality of receiving stations having telephone receivers included in conductors in bridge of the telephone line, and adjustable 10 impedance included in said conductors.

7. A telephone system including a telephone line, a transmitting station at which voice currents are impressed upon the line, a plurality of receiving stations having telephone receivers included in conductors in bridge of the telephone line, and which conductors offer differing degrees of effective 15 resistance to the voice currents impressed thereupon by the transmitting station, the 20 differing degrees of effective resistance when added to the line resistance between any particular station and the transmitting station,

being approximately the same from all stations to the transmitting station.

8. A telephone system including a telephone line, a transmitting station at which voice currents are impressed upon the line, a plurality of receiving stations having telephone receivers included in conductors in bridge of the telephone line, and which conductors offer differing degrees of impedance 25 to the voice currents impressed thereupon by the transmitting station, the differing degrees of impedance when added to the line resistance between any particular station 30 and the transmitting station affording approximately the same effective resistance from all stations to the transmitting station.

In witness whereof, I hereunto subscribe my name this 18th day of July A.D., 1908.

HIRAM D. CURRIER.
